UNITED STATES PATENT OFFICE

2,552,931

COIN BANK WITH REMOVABLE CYLINDERS

Oscar H. Brasier, Tacoma, Wash.

Application April 19, 1949, Serial No. 88,295

1 Claim. (Cl. 232—5)

1

This invention relates to pocket banks, and more particularly, has reference to a coin bank of novel and attractive design, especially constructed in a manner to permit ready substitution of an empty coin-receiving means utilized therein, for one which is full.

An important object of the present invention is to provide a bank of the character stated which can be issued by banks or other savings institutions, as an advertisement and also for the promotion of savings, and which, when used by the banks' depositors, will not require the expenditure of more than a minimum amount of time by the teller or other employee to whom the coin bank is turned over by the customer when the coin bank is full.

Another important object is to provide a coin bank of the type stated which will be simply constructed, durable, will embody no moving parts, and will be attractive in appearance.

Another important object is to provide a coin bank of the character stated which will be equipped to receive paper currency as well as coins.

With the foregoing and other objects in view which will appear as the description proceeds, the invention consists of certain novel details of construction and combinations of parts, herein-after more fully described and pointed out in the claims, it being understood that changes may be made in the construction and arrangement of parts without departing from the spirit of the invention as claimed.

Referring to the drawings

Fig. 1 is a side elevational view of a coin bank constructed in accordance with the invention.

Fig. 2 is an end elevation.

Fig. 3 is a top plan view.

Fig. 4 is a section on line 4—4 of Fig. 3.

Fig. 5 is a section on line 5—5 of Fig. 1.

Referring to the drawings in detail, 5 designates a base which can be of metal, plastic, or any other suitable material. In general conformation, the base is preferably oblong in shape, although the particular shape of the base is not critical to the invention, permitting the shape to be varied as desired. As a matter of fact, the particular shape of the illustrated coin bank is in general not critical to the invention, since obviously design features can be given to a coin bank, varying its general appearance while not changing its mechanical arrangement of parts.

The base 5 is formed in its upper surface, with

2

spaced apart circular recesses 6, receiving the transparent cylinders 7 closed at their lower ends but formed open at their upper ends. The transparent cylinders 7 can be of plastic or any other desired material, and are adapted to be removably but snugly fitted within the recesses 6 of the base.

The spaced apart coin-receiving cylinders 7 extend upwardly from the base into the cover 8, 10 said cover 8 being of the same general shape as the base so far as its outer conformation is concerned, but being of inverted cup-like formation. Thus, the cover 8 is formed with a closed upper end, a side wall depending therefrom, and an open lower end into which extend the coin cylinders 7. It may be noted that the coin cylinders 7 engage tightly the opposite ends of the cover 8, and thus the coin cylinders 7 will provide a guide for depositing the cover 8 upon the base 5 in proper relationship to the base. In other words, the cylinders 7 can serve as guide means for lowering the cover 8 upon the base, and in fact serve as a means for holding the cover to the base except upon the exertion of 20 positive effort to remove the cover from the base.

A lock 9 is preferably provided in the base, adapted to permit the cover to be locked thereto after the cover is mounted in the position illustrated in the drawings. Generally, the bank teller or other employee of the financial institution issuing the coin banks, would be the only one possessing the key, so that when the coin bank is full, the person having the coin bank is required to go to the financial institution for the purpose of having the coin bank opened and the contents removed.

Formed in the end of the cover 8 are the vertically disposed closed slots 10, and graduations or a scale 11 are marked on the outer surface of the cover 8, for the purpose of indicating the number of coins, as for example dimes, contained within the transparent cylinders 7. Thus, for example, when the cylinders 7 are approximately half full, the holder of the coin bank is enabled clearly to see the extent to which the cylinders are filled, and may notice, for example, that there are 30 dimes in each of the cylinders, this being readily observed by comparison of the coin level with the adjacent graduation or scale marking.

In the opposite faces of the cover 8 there can be provided recesses 12, receiving photographs or advertising media 13, and a transparent window or cover 14 can be mounted in said recesses

to prevent soiling of said pictures, as for example snapshots, or advertising media.

It will be noticed that when all the parts are assembled as in Fig. 4, there will be defined in the center of the coin bank a compartment 15 for receiving paper currency. This compartment will be defined between the opposite and spaced apart coin cylinders 7, and the opposite faces of the cover 8.

For the purpose of permitting the deposit of paper currency into the compartment 15, I provide the circular opening 16 formed in the closed upper end of the cover 8, at the center thereof.

For the purpose of permitting dimes or other coins to be deposited in the coin cylinders 7, I provide the inclined coin slots 17 at opposite ends of the cover 8, these inclined slots 17 being so arranged as to cause a coin deposited therein to be dropped directly into the coin cylinders 7, the upper ends of the coin cylinders 7 being closed by the upper end of the cover 8.

In use, the holder of the coin bank deposits coins of the proper denomination in the respective coin cylinders 7, through the coin slots 17. At all times, the user is enabled to know the number of coins within the cylinders and when the cylinders are full, the user goes to the financial institution, where an employee of the institution unlocks the coin bank. Said employee, as will be noted, simply lifts the filled coin cylinders 7 from their recesses 6, and without bothering to count the coins at that particular moment, can give the customer two empty coin cylinders. At any convenient time, filled coin cylinders brought in by customers of the institution can be emptied directly into coin wrappers, this being permitted by reason of the construction of each cylinder 7, which is closed at one end but is open at the other end. Thus, the coins are simply deposited in a conventional coin wrapper by up-ending the coin cylinders 7, and of course, by noting the level of the coins within the coin cylinders, it can be known exactly how much money is represented by said coins within the cylinders.

Advantages of the invention reside in its durability, lack of moving parts, and simplicity of construction. Further important advantages are readily noted as residing in the fact that it is not necessary for the financial institution employee to count the coins in the presence of the customer. All that is necessary is that two other empty coin cylinders be given the customer, in place of the filled coin cylinders which the customer leaves with the institution.

At all times, additionally, the customer is enabled to know how many coins he has in the cylinders, because the cylinders are transparent, and can be viewed through the vertical slots 10 and the coin level readily compared with the scale markings.

It will be understood that the coin bank con-

structed along the lines set forth herein can be varied as to ornamental design, and it is not desired that I be limited to the particular shape and arrangement of the parts, except so far as called for by the claim.

It should be further understood that although, as indicated previously in this specification, a financial institution can keep the key, and unlock the banks, nevertheless it is quite possible that the coin bank might be sold to an individual outright, who would of course be furnished with the necessary key, this being a distinct possibility where, for example, the banks might be sold to customers through the mail to points not serviced by a financial institution and where the cost of mailing the bank back and forth would be prohibitive.

I claim:

A coin bank comprising a base having deep, circular, spaced recesses formed in its top surface; transparent, one-piece coin cylinders of circular cross section having open upper ends and having their lower end portions removably seated in and frictionally gripped by the walls of said recesses, said cylinders extending upwardly in parallel relation from said base a substantial distance; and a one-piece cover of inverted cup-like configuration fitted over the upwardly extended portions of the cylinders and shaped to include a closed upper end and a side wall integral with and depending from said closed end, opposite portions of said side wall being curved to correspond to the curvature of the cylinders and being releasably and frictionally gripped by the upwardly extended portions of the cylinders, said cylinders being otherwise free of attachment to the base and cover and constituting dowel members separably assembling the cover to the base, the curved portions of said side wall having elongated viewing slots extended longitudinally of the upwardly extended cylinder portions, there being coin deposit slots formed in the upper end of the cover and opening into the upper ends of the cylinders.
